UNITED STATES PATENT OFFICE.

WILLIAM W. WEBER, OF FORT MYERS, FLORIDA.

MINER'S COMBINATION-TOOL.

1,263,720.

Specification of Letters Patent. Patented Apr. 23, 1918.

Application filed October 19, 1917. Serial No. 197,450.

To all whom it may concern:

Be it known that I, WILLIAM W. WEBER, a citizen of the United States, residing at Fort Myers, in the county of Lee and State of Florida, have invented certain new and useful Improvements in Miners' Combination-Tools, of which the following is a specification.

This invention relates to combination tools used by miners to prepare fuses in blasting operations; and it consists in the novel construction and combination of the parts hereinafter fully described and claimed.

In the drawings, Figure 1 is a front view of a tool constructed according to this invention. Fig. 2 is a side view of the cutting parts of the tool. Fig. 3 is a plan view of the same. Fig. 4 is a cross-section taken on the line $\alpha-\alpha$ in Fig. 1.

The tool is provided with handle portions 2 and 3, having plates 4 and 5 at their upper end portions. These plates are substantially circular, and they are pivoted together centrally by a bolt or pivot 6. A spring 7 is arranged between the handle portions to normally hold them apart. The plates 4 and 5 are provided with cutting jaws 8 arranged in pairs and spaced at suitable distances apart around the central pivot pin 6, and so that a plurality of cutters is provided.

One plate 4 has a deep notch cut in it, and it has a splitting blade 9 formed on it and extending circumferentially from one side of the notch toward its other side which forms a stop 10.

The other plate 5 has a tubular guide 12 formed on or otherwise secured to it, and

projecting laterally into the notch in the plate 4. One side of the guide 12 has a slot 14 formed in it for the splitting blade 9 to work in, and the tubular guide is arranged radially of the pivot 6. When the handle portions are pushed apart by the spring, the stop 10 comes against the opposite side of the guide tube from the slot 14, so that the cutting edge of the blade is not withdrawn from the slot and is protected from injury by the tube.

The fuse is cut to the required length by means of either pair of cutting blades, and when one pair is too blunt or is otherwise unsuitable another pair can be used.

The end portion of the fuse is then thrust longitudinally into the tubular guide, and is split by means of the splitting blade so as to expose its inflammable core or filling, as is necessary in preparing a fuse for blasting.

What I claim is:

In a fuse splitter, two pivoted plates arranged side by side and provided with handle portions, one plate being provided with a notch having a splitting blade on one side and having a stop on its other side, and the other plate having a tubular guide one side portion of which projects laterally from it into the said notch between the cutting blade and the stop and which is provided with a slot for the cutting blade to work in, said stop operating to limit the outward movement of the blade in the notch.

In testimony whereof I have affixed my signature.

WM. W. WEBER.
